UNITED STATES PATENT OFFICE

BILLIE CLARK, OF WINFIELD, KANSAS

CASING CONNECTION

Application filed April 26, 1929. Serial No. 358,283.

My present invention pertains to casing connections or pipe fishing devices; and it contemplates the provision of such a device possessed of the practical advantages hereinafter ascribed to it over analogous devices at present known in the art.

To the attainment of the foregoing, the invention consists in the improvement as hereinafter described and definitely claimed.

10 In the accompanying drawings forming part of this specification:

Figure 1 is a side elevation of the upper portion of the preferred embodiment of my invention.

15 Figure 2 is a side elevation of the intermediate portion of said embodiment.

Figure 3 is a side elevation of the lower end portion of said embodiment.

20 Figure 4 is a section of the upper portion of the preferred embodiment of the device.

Figure 5 is a section of the intermediate portion of the embodiment.

25 Figure 6 is a section of the lower end portion of the said embodiment.

Figure 7 is an enlarged transverse section taken on the plane indicated by the line 7-7 of Figure 4 looking downwardly.

It will be noted that Figures 1, 2 and 3 read downwardly in the sequence indicated 30 illustrate in elevation the complete device, while Figures 4, 5 and 6 read downwardly in the sequence indicated illustrate the complete device in section.

Similar numerals of reference designate 35 corresponding parts in all the views of the drawings.

Among other elements the preferred embodiment of my invention comprises a body 1 with wrench holds 1^x adjacent to its lower end, Figure 3, a lower guide member 2, Figures 3 and 6, rounded at its lower end 3 and an upper or latch socket member 4. The member 2 is threadedly or otherwise suitably connected in detachable manner at 40 to the lower end of the body 1, Figure 6.

The latch socket member 4 comprises a body of general cylindrical form provided with wrench holes 6 and also with the conventional threaded end-extension 7, Figures 1 45 and 4. In the said body of the member 4

is formed a bore 8, of angular cross section and closed at its upper end and open at its lower end, and in communication with the said bore 8 is a slot 9 and a recess 10, Figure 4. Pivoted at 10^x in the recess 10 is a swingable latch member 12 subject to the influence of a retractile spring 13, which spring 13 is connected at all times to the latch member 12 but is adapted to be connected either to an upper hook 13^a or a lower hook 13^b, the first of said connections being provided in order to enable the spring 13 to maintain the latch member 12 in the position illustrated in Figure 4, and the second of said connections being resorted to when it is desired to use the spring 13 for the yieldable maintenance of the latch member 12 in upright position.

While the bore 8 is referred to as of angular cross section, I deem it proper to say that more correctly the cross section of the bore 8 is of general elliptical form.

The lower or guide member 2 of the device is chambered or bored at 14, Figure 6, and is preferably provided with a longitudinal central aperture 15 extending from said chamber 14 to the lower rounded end of the member.

The body or intermediate member 1, Figures 2 to 6, is provided with a bore 20 of square form in cross section which extends from the upper end of the said body 1 to the lower intermediate point 20^x, Figure 5, and is slightly larger in cross section than the bore 8 of member 4 and is merged at its lower end into a small bore 21, Figures 5 and 6. Carried by the said body 1 are three pairs of dogs, the said pairs of dogs or rather sets of dogs being spaced apart as shown in Figures 1 and 2, and also in Figures 4 and 5. There are four toothed dogs 32 in the upper sets, and said dogs 32 are slidably vertically in recesses 32^x in the body 1 and on flexible strips 33^x which are secured at their upper ends in the body 1 and have their lower portions arranged loosely at the inner side of retaining members 34^x. The retaining members 34^x are connected to the body 1 by screws 35, and the said screws extend loosely through the strips 33^x and support expansion springs 36 which by pressing outwardly against the 95

strips 36^x serve to yieldingly hold the dogs 32 in outwardly extended position.

As appears in Figure 4 the lower end portions of the strips 33^x extend below the retaining members or blocks 34^x for a purpose to be hereinafter set forth.

The intermediate dogs of toothed type and four in number are designated by 37, Figures 2 and 5. These dogs 37 are slidable vertically on flexible strips 38 secured at their upper ends in the body 1, and the lower portions of the said strips 38 are disposed at the inner side of retaining members 39, which are connected to the body 1 by screws 40 on which 10 are expansion springs 41, the province of which is to press the strips 38 outwardly and thereby yieldingly maintain the dogs 37 in outwardly extended positions. The lower ends of the strips 38 are disposed in the upper ends of shoes 42, said shoes 42 being normally arranged as illustrated in Figure 5, and being pivotally connected at 43 to the body 1, which is recessed at 44 for the play of the shoes 42 of which four are employed.

There are four of the toothed dogs 45 complementary to the body 1, Figures 2 and 5. These dogs 45 constitute the lowermost set of dogs and they are associated with lever members 46 pivoted at 47 to the body 1 and movable in slots 48 of said body 1. The said lever members 46 are provided with inclined ribs 49 of dove tail cross section with which ribs the dogs 45 are engaged, and on which ribs the dogs 45 are slidably arranged so that the said dogs 45 are capable of vertical movement relative to the lever members 46.

At 49^x in the body 1 is removably arranged a diametrical headed key which is backed by and normally retained in position by a cap plate 49^a detachably secured by screws to the body 1. This construction is clearly brought out in Figure 5.

At 50, Figures 4 and 5, is a plunger movable in the body 1 and the members 2 and 4. Said plunger 50 has a slot 51 which receives the key 49^x, Figure 5, so that the said key 49^x limits the endwise movement of the plunger 50. The said plunger 50 is also provided with four cam projections 52, movable in slots 53 of the body 1 and designed by co-operation with the lower ends of the strips 32^x to retract or move inwardly the dogs 32, Figures 1 and 4. At its lower end the major portion of the plunger 50, which portion is preferably of square cross section, the plunger is provided with a depending rod 53 on which is a nut or other abutment 54 between which abutment and the abutment 55 in the body 1 is interposed an expansion spring 56, Figure 6. Under normal conditions the said spring 56 serves to yieldingly hold the plunger 50 against upward movement. Manifestly when the plunger 50 is in its lowermost position, the swingable members 46 will be maintained 60 against inward movement as will be readily

understood from Figure 5. When however, the plunger 50 is moved upwardly from the position shown in Figure 5 the lever members 46 will be free to swing inwardly and will carry with them the lowermost dogs 45.

The upper portion 57 of the plunger 50 is reduced and is disposed in the bore 8 of the member 4, and it will be readily noticed that the said reduced portion 57 is provided at 70 58 with a slot for the reception of the latch 12. It will also be readily understood that the said plunger portion 57 corresponds in configuration with the cross section of the bore 8.

When the plunger 50 is in its uppermost position, the dogs 45 will be free to move inwardly relative to the body 1. The novel connection is then ready to be run in pipes, the dogs 32 being held in their inward position while the dogs 37 are free to be pushed 85 inwardly. When the connection runs through the upper section of a parted pipe, the shoes 42 leave the lower end of the upper pipe section, and the dogs 37 are forced outwardly, thereby causing the dogs 37 to take hold of the 90 inside of the pipe, said dogs 37 slipping upwardly on the strips 38 and seating against the body 1. The inclination of the seats complementary to the dogs 37 forces the said dogs 37 outwardly as the dogs slip upwardly relatively to the seats. When the dogs 37 take hold, the body 1 stops and the weight of drilling tools forces the plunger 50 downwardly which brings about release of the dogs 32 and they then take hold of the inside 95 of the pipes. If the body 1 for any reason starts to work downwardly as the dogs 32 are pushed outwardly, the plunger 50 being seated in its lowermost position will force the dogs 45 outwardly into position to enter the 100 upper portion of the lower section of the parted pipes. It will also be understood that when the plunger 50 is driven downwardly, the latch socket member 4 which is to be run on drilling tools in actual practice, will 105 be released from the connection by virtue of the spring 13 lifting the latch 12 out of the slot 58 in the plunger 50. The latch socket member 4 can then be withdrawn from the hole which will prevent stripping jobs by 110 having tools and latch socket member attached. It will also be understood that with the parts positioned as last stated, the connection has taken proper hold in the upper section of a parted pipe and is held up by 115 said section only. The plunger 50 having been moved downwardly as before stated has shoved the dogs 45 outwardly, and is now ready to enter the upper portion of the lower section of parted pipes. At such time the 120 connection has taken proper hold in both the lower and upper sections of parted pipes with the result that through the medium of the connection the said sections of pipes are connected together. The spring 13 is adapted 125

130

to be connected to either the lower fastening 13^b or the upper fastener 13^a shown in Figure 4. When the spring 13 is connected to the upper fastener, the latch socket member 4 is ready to be set over the plunger 50, and when this is done the latch 12 falls through the slot 58 in the plunger 50. The connection is then ready to be picked out of the pipe, and in this connection it will be understood that the connection may be removed from the pipe by pulling upwardly on the plunger 50 if it becomes necessary to rip off pipes. When the plunger 50 is picked upwardly to remove the connection from a hole, all of the dogs swing inwardly and are in the clear and consequently are prevented from catching the inside wall of the pipe while the connection is being removed from the hole.

In other words the dogs are in the same position as when the connection is being lowered in a hole.

When the dogs 32 engage the upper section of a parted pipe the connection will be prevented from working downwardly. Again when the connection is being run in pipe, if the connection stops at any place in pipe, such as might be caused by encountering a dented place in the pipe, the weight of the drilling stem will force the plunger 50 downwardly which will enable the springs complementary to the dogs 32 to force said dogs outwardly and cause them to take proper hold, and in that way prevent the connection from dropping in the hole.

I have entered into a detailed description of the construction and relative arrangement of the parts embraced in the preferred embodiment of invention in order to impart a full, clear and exact understanding of the said embodiment.

I do not desire, however, to be understood as limiting myself to the construction and relative arrangement of parts as disclosed, my invention being defined by my appended claims within the scope of which modifications may be made without departure from my invention.

The spring 13 is hooked to fastener 13^b, Figure 1, for running the casing connection in a hole, while the said spring 13 is hooked to the fastener 13^a as shown in Figure 1 to remove the connection from a hole.

Having thus described the invention, what I claim as new and desire to secure by Letters Patents is:—

1. In a device for the purpose described and in combination, a body, sets of dogs carried by the body and movable relatively thereto, a plunger movable relatively to the body and sets of dogs, one set of dogs being free to move inwardly when the plunger is moved in one direction and being movable outwardly when the plunger is moved in the opposite direction, and cam means comple-

mentary to the plunger and another set of dogs for retracting the latter on movement of the plunger in the first of said directions.

2. In a device for the purpose described and in combination, a body, sets of dogs carried by the body and movable relatively thereto, a plunger movable relatively to the body and sets of dogs, one set of dogs being free to move inwardly when the plunger is moved in one direction and being movable outwardly when the plunger is moved in the opposite direction, cam means complementary to the plunger and the other set of dogs for retracting the latter on movement of the plunger in the first of said directions, dogs spring impelled outwardly and carried by the body between the other two sets of dogs, and shoes pivoted at one end to the body, and having their opposite ends connected with the last named dogs.

3. In a device for the purpose described and in combination, a body, sets of dogs carried by the body and movable relatively thereto, a plunger movable relatively to the body and sets of dogs, one set of dogs being free to move inwardly when the plunger is moved in one direction and being movable outwardly when the plunger is moved in the opposite direction, cam means complementary to the plunger and the other set of dogs for retracting the latter on movement of the plunger in the first of said directions, dogs spring impelled outwardly and carried by the body, shoes pivoted at one end to the body and movable radially with the last named dogs, and a latch socket member detachably connected to the plunger and through the plunger with the body.

4. In a device for the purpose described and in combination, a body having dogs and dog controlling means, in combination with a lower guide member, an upper member separable from the body, a latch carried by the upper member, a plunger movable in and connected to the body and movable in the upper member and adapted to receive the latch, and means for yieldingly holding said plunger against endwise movement.

5. In a device for the purpose described and in combination, a body having dogs, and dog controlling means, in combination with a lower guide member, an upper member separable from the body, a latch carried by the upper member, a plunger movable in and connected to the body and movable in the upper member, and adapted to receive the latch and means for yieldingly holding said plunger against endwise movement; the lower guide member being chambered, and the said means including a rod on the plunger and in said chamber, and a spring on the rod and in the chamber for resisting movement of the rod in one direction.

6. In a device for the purpose described, and in combination, a body having dogs, and

dog controlling means, an upper member separable from the body, a plunger movable in and connected to the body and movable in the upper member, and adapted to receive the latch; a latch in the upper member for the detachable connection of the same to the plunger, and means for retaining the plunger in the body while permitting of endwise movement of the plunger in said member.

7. In a device for the purpose described, and in combination, a body having dogs, and dog controlling means, an upper member, a plunger movable in the body and upper member, a latch in the upper member for the detachable connection of the same to the plunger, and means for retaining the plunger in the body while permitting of endwise movement of the plunger in said member; the plunger being provided with a pendent rod and a spring being interposed between an abutment on said rod and the lower portion of the body.

8. A device for the purpose described, comprising a body, an upper member separable from the body, sets of dogs carried by the body, a latch carried by the upper member, a plunger movable in and connected to the body and movable in the upper member and arranged to receive and cooperate with the said latch, means for yieldingly resisting upward movement of the plunger in the body and member, and a key detachably secured in the body and disposed in a slot in the said plunger.

9. A device for the purpose described, comprising a body, an upper member, sets of dogs carried by the body, a latch carried by the upper member, a plunger movable in the body and the upper member and arranged to cooperate with the said latch, means for yieldingly resisting upward movement of the plunger in the body and member, and a key detachably secured in the body and disposed in a slot in the plunger; the said means for yieldingly resisting endwise movement of the plunger including a rod on the plunger and pendent therefrom, and a spring on the rod and interposed between an abutment thereof and the lower portion of the body, and the body being equipped with a chambered guide member receiving the said rod and spring and detachably connected to the lower end of the body.

10. In a device for the purpose described, and in combination, a body, dogs swingably connected with the body, said dogs having extended strips, and said dogs being spring influenced whereby they are yieldingly maintained in extended position, and a plunger movable endwise relatively to the body and having cam means arranged to cooperate with the said strips of the said dogs for the retraction of the dogs.

11. In a device for the purpose described, and in combination, a body, dogs swingably

connected with the body, said dogs having said strips, and said dogs being spring influenced whereby they are yieldingly maintained in extended position, and a plunger movable endwise relatively to the body and having cam means arranged to cooperate with the said strips of the said dogs for the retraction of the dogs; the said dogs being slidable as well as swingable relatively to the body and being arranged in certain position to engage and be backed by the body.

12. In a device for the purpose described, and in combination, a body with recesses, the inner walls of which are inclined, flexible strips disposed in said recesses and connected at their upper ends with the body, dogs slidable on said strips, spring means for impelling the lower portions of the strips outwardly, means carried by the body for limiting the outward movement of the strips, and a plunger movable in the body and relatively thereto, and having cam means for cooperating with the lower portion of said strip for the retraction of said dogs.

13. In a device for the purpose described, and in combination, a body, said body having recesses in its exterior, spring strips arranged in said recesses and connected at their upper ends to the body, dogs slidable in said recesses and on said strips, spring means for impelling the lower portions of the strips outwardly, means carried by the body for limiting the outward movement of the lower portions of the strips, and shoes exteriorly of the body and connected at their lower ends thereto and having their upper ends engaged with and adapted to move the lower portions of the strips.

14. In a device for the purpose described, and in combination, a body having longitudinal slots, a plunger movable endwise in and relatively to said body, lever members pivoted to the body and arranged in said slots and having inclined ribs, and dogs held to and slidable on said ribs of the lever members, said lever members movable outwardly by the plunger and adapted to swing inwardly when released by the plunger.

15. In a device for the purpose described and in combination, a body, said body exteriorly recessed, spring pressed dogs carried by the body and movable in said recesses, and longitudinally disposed controlling shoes, said shoes pivotally connected with the body and connected with the dogs.

16. In a device for the purpose described and in combination, a body equipped with dogs, a member superposed on and separable from the body and equipped with a latch, a plunger movable relatively to the body and engaged by said latch, and means cooperating with the plunger and the body for yieldingly resisting endwise movement of the plunger in one direction.

17. In a device for the purpose described and in combination, a body, a member superposed on and separable from the body and equipped with a latch, a plunger engaged by said latch and movable in and relatively to the body and having cam means, a set of dogs carried by the body and controllable by the plunger, a second set of dogs carried by the body and controllable by the cam means of the plunger, a third set of dogs carried by the body and spring impelled outwardly, and movable shoes carried by the body and engaged with the last named set of dogs for the control of the latter.

15 In testimony whereof I affix my signature.
BILLIE CLARK.
